MINIATURE FLUORESCENT AND/OR
GLOW LAMP

Chalmers Morehead, East Orange, N. J., assignor
to Westinghouse Electric Corporation, East
Pittsburgh, Pa., a corporation of Pennsylvania

Application December 20, 1943, Serial No. 514,960

11 Claims. (Cl. 176—122)

This invention relates to miniature negative-glow lamps, and, more particularly, those in which the enclosing envelope is coated with fluorescent material in order to adapt them to function as small decorative lamps.

The primary object of my invention, generally considered, is to produce a miniature lamp of the negative-glow, gaseous-conduction type in which the envelope may be coated with fluorescent material to give it a desired color to adapt it for decorative purposes.

Another object of my invention is to provide a small Christmas tree lamp adapted for the production of a more desirable color effect than incandescent filament lamps, while running cooler and thereby consuming a correspondingly smaller amount of energy.

A further object of my invention is to produce a small low-power self-starting ultraviolet, or fluorescent lamp to produce white or colored light for decorative or other purposes, or one to be used as a source of ultraviolet in the 3600 A. U. region.

A still further object of my invention is to produce a miniature low-power, self-starting, fluorescent and/or glow lamp in which the source of radiation is a pair of coiled coil filaments coated with electron-emission material, with adjacent ends connected and supported, diverging from one another, and having their remote ends secured to supporting leads, whereby when energized a glow discharge occurs between the remote end portions, activating a suitable phosphor, if disposed on the lamp envelope, for the production of light of the desired color.

Other objects and advantages of the invention, relating to the particular arrangement and construction of the various parts, will become apparent as the description proceeds.

Referring to the drawing illustrating preferred embodiments of my invention to scale;

Fig. 1 is an elevational view, shown full size in the original drawing, of a fluorescent lamp embodying my invention.

Fig. 2 is an enlarged axial sectional view of the lamp of Fig. 1, showing the enclosed mount in face elevation.

Fig. 3 is an edge elevational view of the mount shown in Fig. 2.

Fig. 4 is a perspective view of a mount of another embodiment of my invention.

Fig. 5 is a view corresponding to Fig. 4, but illustrating a mount of still another embodiment of my invention.

Fig. 6 is a circuit diagram of lamps embody-

ing my invention in series with a ballast lamp.

Fig. 7 is a circuit diagram of a lamp embodying my invention, in series with the filaments of a plurality of radio tubes.

5 Referring to the drawing in detail, and first considering the embodiment of my invention illustrated in Figs. 1, 2, and 3, there is shown a lamp 11 particularly adapted for operation with seven others and a suitable ballast resistor in series in a string, as for Christmas tree decoration on a domestic 110 volt circuit. Said lamp comprises an envelope 12, which may be formed of ordinary soft glass, Corex, or other ultraviolet transmitting glass and correspond in size with 10 such usually employed for Christmas tree lamps, said envelope enclosing a mount 13 which may be sealed therein by the well-known method termed "butt sealing," or, if not coated, as described and claimed in the Carpenter Patent No. 2,235,515, dated March 18, 1941.

15 The mount 13 may be very simply constructed of a glass bead 14 through which supporting leads 15 and 16 of "dumet" or other suitable material extend, and to the inner ends of which are connected, as by spot welding, the ends of a filament 17. The filament 17, in the present embodiment, 20 comprises two sections 18 and 19, each consisting of a coiled coil filament of tungsten, the adjacent ends of said sections being connected by 25 a straight portion, which is in turn connected to a center or intermediate support, which may take the form of a wire spud 21, embedded in the bead 14. The straight end terminals of the sections 18 and 19 are in turn connected to the inner or 30 free ends of the supporting leads 15 and 16, which respectively preferably lie between said coiled-coil sections and the envelope 12 and are desirably bent so that end portions 22 and 23 point toward one another. This arrangement reduces bulb 35 blackening, as compared with the reverse arrangement in which the spud 21 would be longer than those portions of the supporting leads on the same side of the bead 14.

40 A preferred embodiment of my invention involves making the coiled coils 18 and 19 about 6 mm. long, as by taking a suitable length, such as about 438 mm. of 1.21 mil tungsten filament, winding it on a primary mandrel 2.4 mils in diameter, and then winding the two coils so 45 formed on a secondary mandrel 9.1 mils in diameter, thereby giving a double coiled coil filament adapted for glow lamp operation when a potential of about 10 volts is applied thereto. The supporting portions 22 and 23 of the leads 15 and 16 are desirably so disposed with respect to one

another and the intermediate support 21, that the V shaped or "hairpin" filament 17 has its remote ends spaced from about 2 to 5 mm. apart, forming an open thin isosceles triangle.

The coils 18 and 19 are coated with the usual cathode electron-emission mixture containing barium carbonate, one of the other alkaline earth metal carbonates, or a mixture of two or more thereof. By making the sections 18 and 19 of the filament 17 as coiled coils, a larger resistor value, where a given size of filament is employed, may be concentrated in a given space, and the emission mixture when applied thereto is trapped therein and prevented from flaking off in service. Inasmuch as the bulk of the produced discharge occurs between the remote end portions of the coils 18 and 19, it is not necessary to coat more than about half of each of said coils, that is, the remote end portions thereof, although it is not harmful to have the whole length of each coil coated with such emission material.

If it is intended to use the lamp as one of the fluorescent type, the bulb or envelope 12 is coated on the inside with one of the usual phosphors for producing light of the desired color or in the near ultraviolet. The exhaust procedure and cathode treatment to remove carbon dioxide is similar to that employed in any of the hot cathode fluorescent lamps. The completed lamp desirably has an inert gaseous filling, such as argon at a pressure of about 4 mm., said gas being admixed with small amount of mercury, as by placing a small pellet of that metal 20 in the envelope. It is tipped off as indicated at 24 and desirably has a standard miniature screw-threaded base 25 applied thereto, as by cement 26, one lead being connected to the shell 27 of the base and the other to the center contact 28 thereof.

When such a lamp, suitably ballasted, is energized by alternating current applied to the leads 15 and 16, the coated coils 18 and 19 are first heated to electron emission temperature and then a discharge takes place between parts thereof near the connections with the lead portions 22 and 23. This results in the formation of a cathode glow around the coils, involving the production of a copious amount of ultraviolet radiation which, because of the mercury, involves a large proportion of such in the neighborhood of 2537 A. U. Such radiation activates the phosphor or fluorescent coating 29, if present on the envelope 12. If it is desired to use such a lamp to generate such radiations of 2537 A. U., the envelope should be made of glass permeable thereto, such as Corning #972, high transmission ultraviolet glass, which is a form of Corex glass, and the fluorescent coating omitted.

The lamp current passes partly through the coils and partly as the glow discharge. An increase in the total current normally increases the proportion of current that passes as the discharge and reduces the total voltage drop across the lamp. With a lamp having coils as described, the discharge begins when the current exceeds .1 ampere. When the current rises to .15 ampere, the lamp glows brightly. The voltage drop across the lamp does not deviate much from 10 volts, but has a tendency to fall slightly with an increase in the current.

It will be understood that the fluorescent material or phosphor may be employed on the bulb in order to give desired colors, as for Christmas tree decoration. Such lamps may also be used in radio receivers in series with the tubes or cathode filaments thereof. In this instance the lamps

5 10 15 20 25 30 35 40 45 50 55 60 65 70 75

can be used to give near ultraviolet for "black light" illumination of the dials. As such a lamp produces some radio interference it is desirable to minimize this by employing a small condenser, which may be in the base of the lamp in parallel with the filament thereof.

Referring now to the embodiment of my invention illustrated in Fig. 4, there is shown a mount 13^a which may be used as an alternative for the mount 13 of the preceding embodiment. This mount comprises a flare 31 from which supports 32, 33 and 34 project, all of which are desirably formed of nickel. The supports 32 and 33 connect with the leads 15^a and 16^a, as in the press 35, while the support 34 is merely a spud projecting therefrom. The filament 17^a may be identical with the filament 17 of the preceding embodiment. The flare 31 is sealed to an envelope or bulb (not shown) in the usual manner when using such a mount, rather than by the butt-sealing method of the first embodiment.

Referring now to the embodiment of my invention illustrated in Fig. 5, there is shown a construction identical with that of Fig. 4 except that the plane of the filament 17^b, instead of approximately including the lamp axis or extending lengthwise of the bulb, is generally perpendicular to the said axis. As in the preceding embodiment, however, its remote ends are connected to supports 32^b and 33^b, which may be of material corresponding with supports 32 and 33. The connecting non-coiled portion between the adjacent ends of the coils 18^b and 19^b is desirably united, as by spot welding, to intermediate support 34^b, which may correspond generally with support 34 of the preceding embodiment, except that it is longer and has an angular projection in order to provide the desired distance between the free end portion thereof and the lamp axis. The free end portions of the supports 32^b and 33^b, instead of being bent toward one another, like the portions 22 and 23 of the first embodiment, are desirably offset from the press-enclosed portions by bending, as illustrated, so that the distance between the free end of the support 34^b and each support 32^b and 33^b may be approximately 9 mm. while the distance between the supports 32^b and 33^b may be between 2 and 5 mm.

Fig. 6 represents preferably eight lamps 11 which may be used for Christmas tree illumination, in series with one another and a ballast lamp 36, across a domestic potential of say 110 volts. Owing to the variation in voltage on household circuits, a most suitable ballast is a tungsten filament lamp, such as illustrated, or a resistor preferably made of metal wire of a material which has a positive temperature coefficient of resistivity, such as iron. The magnitude of the resistor used in such an arrangement is desirably in the neighborhood of 200 ohms, so that current after stabilization is about 150 milliamperes.

A desirable form of ballast lamp 36 is one containing a tungsten filament of such proportions that when operated in series with a selected number of glow lamps 11, its filament gives off some light so that it may function as one of the lamps in the series. Its envelope may be coated with a pigment of the desired character, like an ordinary Christmas tree lamp if the others of the series are to be used for that purpose, the envelope being uniform in size and shape as compared with those of the other lamps. The ballast lamp, therefore, may be readily and desirably formed as an incandescent lamp, having a coating applied either to the outside, as distinguished

from the inside, or a darker color than the fluorescent material on the other lamps, whereby it may easily be identified.

Fig. 7 shows a lamp 11 embodying my invention in series with the filament-heating circuit of a plurality of radio tubes 37 which may comprise part of a receiving set, said tube cathode-heating filaments 38 serving as the ballast for the lamp 11. Radio interference may be minimized by using a small condenser, as that designated 39, which may be in the lamp base, in parallel with the lamp. The lamp 11 may serve to furnish near ultraviolet and/or visible radiations for "black light" and/or other illumination of the dial or dials.

From the foregoing it will be seen that I have devised a miniature fluorescent, ultraviolet, and/or glow lamp, particularly adapted for decorative purposes, which has the following advantages over the customary type of filament lamps for series operation:

1. Low power consumption.
2. Cooler operation.
3. Colors not obtainable by pigment filters.
4. Readily identified in case of burn-out.

Ordinarily when a filament lamp in series fails, all the lamps in the series go out and it is time-consuming to identify the burn-out. When a lamp embodying my invention fails, it is ordinarily through loss of emission material so that the failure is merely in the formation of the glow. When this occurs enough current passes through the filament to permit the remaining lamps in the series circuit to continue operation. Hence defective or worn out lamps can be easily identified.

5. Longer life.

It will be understood that the same, or a different form of envelope or bulb may be used for enclosing the mounts of the embodiments of Figs. 4 and 5 as is used for that of Fig. 3. It will also be understood that I may use a different form of bulb for enclosing the mount of the embodiment of Fig. 2, although the shape illustrated is believed preferable for that type of mount. For the type of mount illustrated in Fig. 5 a spherical bulb or one not as long as that of Fig. 2 may be preferable.

When it is desired to take the light mainly from the side, or perpendicular to the axis of the lamp or base thereof, the form of mount illustrated in Figs. 3 and 4, is believed to be preferred. However, when the light is taken mainly from the end, or axially, of the lamp, the form of mount of Fig. 5 is believed to be more desirable. It will be understood that in any form, the dumet, or other lead-in conductor, may be continued to form internal supporting leads or may be joined, preferably in the press, with nickel or other internal supporting portions.

While the angle between the coils may be varied, a small angle, or one in which the remote ends of the coils are spaced a relatively short distance, appears to be the more desirable, as making a lamp which is more efficient than one in which the coils are disposed at a large angle to one another. It will also be understood that although I have disclosed a preferred embodiment of my filament, yet I do not wish to be limited thereto as other forms may be satisfactorily employed.

Although preferred embodiments of my invention have been disclosed, it will be understood

that modifications may be made within the spirit and scope of the appended claims.

I claim:

1. A negative-glow lamp of the gaseous-conduction type comprising a V shaped filament, electron-emission material thereon, an enclosing envelope and an inert gaseous filling in said envelope, whereby when a suitable potential is impressed at the ends of said filament, first passage of current along with heating to electron emission temperature and then a glow discharge occurs between only the remote end portions thereof in addition to the passage of the current along said filament.
- 10 2. A negative-glow lamp of the gaseous-conduction type comprising a pair of coils of tungsten filament, an intermediate support to which adjacent joined ends of said coils are connected, an enclosing envelope, interior supporting leads extending beyond said support and to which the remote ends of said coils are connected and spaced a short distance apart so as to form a narrow V, electron-emission material on said coils, and an inert gaseous filling admixed with mercury vapor in said envelope, whereby when a suitable potential is impressed at the remote ends of said coils, the latter first pass current therealong and heat to electron-emitting temperature, and then a glow discharge occurs between the supporting-lead-connected portions of said coils in addition to the passage of the current along said filament.
- 20 3. A negative-glow lamp of the gaseous-conduction type comprising a filament in two sections extending at a small angle to one another, the free ends of said sections being spaced a small distance, such as between two and five millimeters, electron-emission material on said filament sections, an enclosing envelope, and an inert gaseous filling admixed with mercury vapor in said envelope, whereby when a suitable potential is impressed at the ends of said filament, the latter is heated to electron-emitting temperature by the flow of current along the filament and a glow discharge occurs between the remote end portions thereof in addition to the passage of the current along said filament.
- 30 4. A negative-glow lamp of the gaseous-conduction type comprising a pair of coils of tungsten filament joined at adjacent ends and there connected to an intermediate support, an enclosing envelope, interior supporting leads which extend beyond said support and have inwardly bent end portions to which the remote ends of said coils are connected and spaced a short distance apart, so as to lie at a small angle with respect to one another, each of said coils being coated with alkaline earth emission material, and an inert gaseous filling admixed with mercury vapor in said envelope, whereby when a suitable potential is impressed at the remote ends of said coils a glow discharge occurs therebetween in addition to the passage of the current along said filament.
- 40 5. A negative-glow lamp of the gaseous-conduction type comprising a V shaped filament, electron-emission material thereon, an enclosing envelope the inner surface of which is coated with fluorescent material, and an inert gaseous filling admixed with mercury vapor in said envelope, whereby when a suitable potential is impressed upon said filament, a glow discharge occurs between portions thereof in addition to the passage of the current along said filament and the fluorescent material is activated.
- 50 6. A negative-glow lamp of the gaseous-conduction type comprising a pair of coils of tungsten filament joined at adjacent ends and there connected to an intermediate support, an enclosing envelope, interior supporting leads which extend beyond said support and have inwardly bent end portions to which the remote ends of said coils are connected and spaced a short distance apart, so as to lie at a small angle with respect to one another, each of said coils being coated with alkaline earth emission material, and an inert gaseous filling admixed with mercury vapor in said envelope, whereby when a suitable potential is impressed at the remote ends of said coils a glow discharge occurs therebetween in addition to the passage of the current along said filament.
- 60 7. A negative-glow lamp of the gaseous-conduction type comprising a V shaped filament, electron-emission material thereon, an enclosing envelope the inner surface of which is coated with fluorescent material, and an inert gaseous filling admixed with mercury vapor in said envelope, whereby when a suitable potential is impressed upon said filament, a glow discharge occurs between portions thereof in addition to the passage of the current along said filament and the fluorescent material is activated.
- 70 8. A negative-glow lamp of the gaseous-conduction type comprising a pair of coils of tungsten filament joined at adjacent ends and there connected to an intermediate support, an enclosing envelope, interior supporting leads which extend beyond said support and have inwardly bent end portions to which the remote ends of said coils are connected and spaced a short distance apart, so as to lie at a small angle with respect to one another, each of said coils being coated with alkaline earth emission material, and an inert gaseous filling admixed with mercury vapor in said envelope, whereby when a suitable potential is impressed at the remote ends of said coils a glow discharge occurs therebetween in addition to the passage of the current along said filament.
- 80 9. A negative-glow lamp of the gaseous-conduction type comprising a V shaped filament, electron-emission material thereon, an enclosing envelope the inner surface of which is coated with fluorescent material, and an inert gaseous filling admixed with mercury vapor in said envelope, whereby when a suitable potential is impressed upon said filament, a glow discharge occurs between portions thereof in addition to the passage of the current along said filament and the fluorescent material is activated.
- 90 10. A negative-glow lamp of the gaseous-conduction type comprising a pair of coils of tungsten filament joined at adjacent ends and there connected to an intermediate support, an enclosing envelope, interior supporting leads which extend beyond said support and have inwardly bent end portions to which the remote ends of said coils are connected and spaced a short distance apart, so as to lie at a small angle with respect to one another, each of said coils being coated with alkaline earth emission material, and an inert gaseous filling admixed with mercury vapor in said envelope, whereby when a suitable potential is impressed at the remote ends of said coils a glow discharge occurs therebetween in addition to the passage of the current along said filament.
- 100 11. A negative-glow lamp of the gaseous-conduction type comprising a pair of coils of tungsten filament joined at adjacent ends and there connected to an intermediate support, an enclosing envelope, interior supporting leads which extend beyond said support and have inwardly bent end portions to which the remote ends of said coils are connected and spaced a short distance apart, so as to lie at a small angle with respect to one another, each of said coils being coated with alkaline earth emission material, and an inert gaseous filling admixed with mercury vapor in said envelope, whereby when a suitable potential is impressed at the remote ends of said coils a glow discharge occurs therebetween in addition to the passage of the current along said filament.

6. A negative-glow lamp of the gaseous-conduction type comprising a pair of coils of tungsten filament, adjacent ends of which are joined and connected to an intermediate support, an enclosing envelope, interior supporting leads to which the remote ends of said coils are connected in order to space them a short distance apart so that they make a narrow angle with respect to one another, each lead lying between the coil to which connected and the adjacent wall portion of said envelope to reduce blackening, electron-emission material on said coils, and an argon filling admixed with mercury vapor and at a pressure of about four millimeters in said envelope, whereby when a suitable potential is impressed on said coils they heat to electron-emitting temperature and a glow discharge occurs between portions thereof in addition to the passage of the current along said filament.

7. A negative-glow lamp of the gaseous-conduction type comprising an enclosing envelope, a mount therein formed as a pair of leads extending through a glass bead, a spud upstanding from said bead, relatively short as compared with the lead sections on the same side of said bead, and disposed between but offset from the plane of said lead sections, a filament comprising a pair of connected coils coated with electron-emission material, remote ends of said coils being connected to the free ends of said supporting leads therebeyond, and the connected adjacent ends of which are fastened to said spud therebetween, holding said filament with the coils making a small angle therebetween, and argon admixed with mercury vapor contained in said envelope so that a glow discharge develops during normal operation in addition to the passage of the current along said filament.

8. An ultraviolet radiations generator comprising a negative-glow lamp of the gaseous-conduction type having a V shaped filament, each side of said V comprising a coiled-coil, electron-emission material trapped in the meshes of said coils, an enclosing envelope of ultraviolet transmitting material and an inert gaseous filling admixed with mercury vapor in said envelope, whereby when a suitable potential is impressed at the ends of said filament, first heating to electron emission temperature and then a glow discharge and generation of ultraviolet radiations occurs between the remote end portions thereof in addition to the passage of the current along said filament.

9. In combination with a plurality of decorative negative-glow lamps of the gaseous-conduction type and suitable for Christmas tree illumination, each lamp comprising a V shaped filament, electron-emission material thereon, an enclosing envelope coated with fluorescent ma-

5 terial, and an inert gaseous filling admixed with mercury vapor in said envelope, whereby when a suitable potential is impressed at the ends of said filament a glow discharge occurs between remote end portions thereof in addition to current passing along the entire filament, an incandescent decorative lamp in series with all of said glow lamps and comprising a filament in an envelope uniform in size and shape with those 10 of said glow lamps, whereby it serves as a ballast for said glow lamps when the whole series is energized from a source of potential, while appearing to be the same as one of the series.

10. In combination, a radio receiving set involving a plurality of receiving tubes containing cathode-heating filaments, a negative-glow lamp of the gaseous-conduction type comprising a V shaped filament, electron-emission material thereon, an enclosing envelope, and an inert 15 gaseous filling admixed with mercury vapor in said envelope, in series with a plurality of said cathode heating filaments, whereby the latter serve as ballast for said negative-glow lamp, and the glow lamp may serve for illuminating a desired portion of the receiving set.

11. A negative glow lamp of the gaseous conduction type having an incandescent filament comprising about 438 millimeters of 1.21 mil tungsten wire, wound as a pair of coils connected by an uncoiled section, each coil being about 6 20 millimeters long and formed by winding about a 2.4 mil primary mandrel and then wound about a 9.1 mil secondary mandrel, the remote portions of said coils having trapped therein an alkaline 25 earth electron-emission mixture, said coils diverging from the uncoiled connection at an acute angle, so that the remote coil ends are spaced from 2 to 5 millimeters, an enclosing envelope, 30 interior supporting leads extending from a glass element in said envelope, lying alongside said coils, disposed between the same and said envelope, and formed with end portions inturned and connected to the remote ends of said coils, an interior intermediate support extending from 35 said glass element in the same general direction as the supporting leads, connected to the uncoiled connecting section of said filament, and holding it closer to said glass element than the remote ends of said coils, and an argon filling in 40 said envelope at a pressure of about 4 millimeters, whereby when a potential of about 10 volts is impressed on said coils in series, they pass current, heat to electron-emitting temperature, and a 45 glow discharge occurs between the portions thereof which carry the electron-emission material in addition to the passage of the current along said filament.

CHALMERS MOREHEAD,
